UNITED STATES PATENT OFFICE

163,305

SWISS WAFER BAKER

Timothy Mojonnier, Oak Park, Ill., assignor to
Mojonnier Bros. Co., Chicago, Ill., a corpora-
tion of Illinois

Application September 28, 1950, Serial No. 12,378

Term of patent 14 years

(Cl. D81—10)

To all whom it may concern:

Be it known that I, Timothy Mojonnier, a citizen of the United States, residing at 842 Columbian Avenue, in the village of Oak Park and State of Illinois, have invented a new, original, and ornamental Design for a Swiss Wafer Baker, of which the following is a specification, reference being had to the accompanying drawings, forming a part hereof.

Figure 1 is a front perspective view of a swiss wafer baker, embodying my new design in baking position;

Figure 2 is a front perspective view thereof in open position; and

Figure 3 is an enlarged detail view of the segments shown in Figure 2.

Referring to Fig. 1, the opposite side and back not shown are substantially plain and a contin-

uation of the general conformation shown in the front view.

I claim:

The ornamental design for a swiss wafer baker, as shown and described.

TIMOTHY MOJONNIER.
